CLAIM

The ornamental design for a capsule, as shown and described.

DESCRIPTION

FIG. 1 is a top perspective view of a capsule showing my new design;

FIG. 2 is a bottom perspective view thereof;

FIG. 3 is a front view thereof, the rear, left and right side views being identical;

FIG. 4 is a top view thereof;

FIG. 5 is a bottom view thereof;

FIG. 6 is another top view thereof, showing the word "TEXT" in broken lines;

FIG. 7 is a top view of a second embodiment thereof, the bottom perspective, front, rear, left and right side and bottom views being identical to those of the first embodiment; and, FIG. 8 is another top view thereof, showing the word "TEXT" in broken lines.

The dashed broken lines illustrate the capsule, the contents of the capsule and the ornamentation "text" and form no part of the claimed design. The oblique shade lines within the solid line circle illustrate transparency; the horizontal parallel shade lines illustrate an opaque surface.
